UNITED STATES PATENT OFFICE.

HARRY L. WILSON, OF PORT TOWNSEND, WASHINGTON.

MUSIC-LEAF TURNER.

No. 801,953.

Specification of Letters Patent.

Patented Oct. 17, 1905.

Application filed December 1, 1904. Serial No. 235,104.

To all whom it may concern:

Be it known that I, HARRY L. WILSON, a citizen of the United States, residing at Port Townsend, in the county of Jefferson and State 5 of Washington, have invented certain new and useful Improvements in Music-Leaf Turners; and I do hereby declare the following to be a full, clear, and exact description of the invention, such as will enable others skilled in 10 the art to which it appertains to make and use the same.

This invention, which relates to music-leaf turners, has for its object the production of an appliance of this character employing a plurality of leaf-turning elements successively active to turn such leaves, each element after 15 action being automatically replaced by the next element.

The nature of the invention will be readily 20 comprehended, reference being had to the following detailed description and to the accompanying drawings illustrating the music-leaf turner in its preferred form of embodiment, it being understood that various changes 25 and modifications may be made therein without exceeding the scope of the concluding claims.

In the drawings, Figure 1 is a front elevation 30 of a music-leaf turner embodying the invention. Fig. 2 is an elevation of one side of the same. Fig. 3 is an elevation of the other side of the same. Fig. 4 is a horizontal section on line 4 4 of Fig. 2. Fig. 5 is a vertical section on line 5 5, Fig. 4. Fig. 6 is 35 a vertical sectional view on line 6 6, Fig. 4.

Referring to the drawings by numerals, 1 designates the music-leaf turner, which consists of a tubular casing, through the center of which extends a shaft 2, the ends of the 40 shaft projecting beyond the top and bottom of the casing and entering sockets or recesses provided in a supporting-rack. (Not shown.) The casing is formed of two sections, which may be of equal length, the lower section 3 being immovable and the upper section 4 being rotatable on the shaft for a purpose presently to be explained.

The lower casing-section 3 is equipped in its interior with oppositely-disposed tubes 5 6 and the lower casing-wall is provided at its opposite sides with vertical slots 7 8, opening, respectively, into the tubes 5 6.

9 9 denote the leaf-turning elements, each consisting of an arm which may be headed at 55 its outer end, as shown, and which conforms at its inner or butt end 10 to the tubes 5 and 6,

said butt-end being relatively smaller than the cross-sectional area of the tube, whereby said butt-end is freely slideable therein. The arms, of which there may be any number dependent 60 upon the requirements, are inserted at their butt-ends in the tube 5 through an opening or slot extension 11 in the lower casing-wall and toward the lower end of the latter, said opening being in communication with the 65 tube 5. The arms project through and beyond the slot 7 and are vertically slideable therein. As will presently be explained, the leaf-turning elements are successively brought into position to be carried and horizontally 70 swung by the rotatable upper casing-section 4, and to accomplish this vertical feed of said elements a spring 12 is provided in the tube 5, and below said elements is a follower 13, equipped with a handle 14 and interposed 75 between said spring and the lowermost leaf-turning element.

To permit the ready insertion of the elements or arms through the opening 11, as above stated, a slot extension 15 is provided 80 in the lower casing-section wall at a right angle to and communicating with the slot 7 below the opening 11, whereby said follower may, after being depressed, be turned slightly to engage with the upper wall of said slot 15, 85 whereby it is locked in this position against the action of the spring. At the lower end of the slot 8 is an enlargement 16 of sufficient area to allow of the ready withdrawal of the elements or arms. The lower casing-section 90 is fastened against turning on the fixed shaft 2, preferably by a pin 17 passing through said shaft and a sleeve 18. The upper casing-section is rotatable on the shaft, shaft-bearings being provided in an upper head 19 and a block 95 20 fastened in said section toward the lower end thereof. The lower end of the upper casing-section is provided at opposite sides with slots 21 and 22, which normally register, respectively, with the slots 7 and 8 in the lower 100 casing-section. The block 20 is located in the upper casing-section to provide between its under side and the top of the lower casing-section a recess of sufficient size to accommodate the butt-end of a single element or arm, 105 whereby said elements or arms are successively carried by the upper casing-section in its rotative movement. The slots 21 and 22 are of sufficient vertical dimension to accommodate the arm portion of an element. The 110 upper casing-section is rotated by the action of a spring 2', coiled around the shaft and se-

cured at its ends, respectively, to said shaft and the head 19. The spring is wound to give the requisite tension for movement of the leaf-turning elements by rotating said section, the 5 latter being held, after the winding step, by a dog 23, carried by the lower casing-section engaging either one of two stops 23', projecting laterally from the lower end of the upper casing-section. The dog is provided at its 10 upper end with a beveled side, whereby it is automatically depressed in the winding movement of the upper casing-section. The upper end of the dog is exterior to the casing-section, whereas it is preferred that the stem by 15 which hand movement of the dog is obtained shall be located within the lower casing-section, and to this end the stem is offset, as at 24, and is slidable in a slot 25 in the section wall. The stem 26 projects through and beyond 20 the head 27 of the lower casing-section and terminates in a handle 28, which normally engages the under side of said head, as shown in Figs. 2 and 3. Said stem and dog are normally elevated by the action of a coil-spring 29, secured at its ends to the stem and 25 said head.

In operation in order to adjust the device the lower leaves of the music are cut from the bottom a distance equal to the height of an 30 element or arm in its active position. An element or arm is then set behind each leaf to be turned, and either before or after this step the upper casing-section is wound. The spring 12 operates to force the uppermost element 35 or arm into the recess and the slot 21 in the upper casing-section.

It will be understood from the foregoing that the upper casing-section is locked against operative rotation by the engagement of the 40 dog with one of the shoulders 23', and when it is desired to turn a leaf the handle 28 is seized by the performer and moved downwardly, thereby depressing the dog and disengaging it from the adjacent stop 23', whereupon 45 the upper casing-section is automatically revolved to carry the uppermost element or arm and the music-leaf engaged thereby sufficiently to cause complete turning of said leaf. The upper casing-section is provided 50 interiorly at its lower end with stops 30, which act to positively move the elements or arms in the rotative movement of the upper casing-section until said elements or arms are caught by a stop 31, projecting from the upper 55 end of the lower casing-section. The position of this stop 31 is such as compels the registering of the vertical slots in the upper and lower casing-sections, whereby the uppermost element or arm after accomplishing 60 the turning of the leaf falls vertically through the tube and slot 6 8 and the device is reset for the next operation. This traverse of an element or arm takes place after each leaf-turning operation, each element after being moved 65 dropping in the tube and slot 6 8, from whence

they may be successively withdrawn through the opening 16, as above stated. The elements or arms are therefore brought successively into and out of action, an inactive element being replaced by the next succeeding 70 active element, the movements of the elements being manually controlled by manipulation of the handle 28.

I claim as my invention—

1. In a music-leaf turner, a plurality of leaf-turning elements, means for moving said elements bodily successively into active position and means for successively operating said elements while in active position to turn the leaves. 75

2. In a music-leaf turner, a plurality of leaf-turning elements, means for moving said elements bodily successively into active position and spring-propelled means for successively operating said elements while in active position to turn the leaves. 80

3. In a music-leaf turner, a plurality of leaf-turning elements, means including a spring for moving said elements bodily successively into active position, spring-propelled means for successively operating said elements while in active position to turn the leaves, and hand means for controlling the operation of said elements. 90

4. In a music-leaf turner, a leaf-turning element, means for elevating said element bodily into active position and means for horizontally swinging said element from its active position to turn a leaf. 95

5. In a music-leaf turner, a leaf-turning element, means for elevating said element bodily into active position, means for horizontally swinging said element from its active position to turn a leaf, and a support for said element during its swinging movement said support terminating to permit the depression of said element at the end of its swinging movement. 100

6. In a music-leaf turner, a leaf-turning element, means including a spring for elevating said element bodily into active position, normally locked means including a spring for horizontally swinging said element from its active position to turn a leaf, hand-controlled means for releasing said last-named means, and a support for said element during its swinging movement said support terminating to permit the depression of said element at the end of its swinging movement. 110

7. In a music-leaf turner, a lower fixed casing, an upper spring-rotated casing, hand-controlled means for locking and releasing the upper casing, a plurality of leaf-turning elements vertically movable in the lower casing to successively occupy a recess in the upper casing, and a spring in the lower casing to move said elements. 120

8. In a music-leaf turner, a lower fixed casing having therein oppositely-disposed vertical tubes and vertical slots in its walls at said tubes, leaf-turning arms slidably arranged at 125

their inner ends in one of the tubes and slots, a spring for moving said arms in said tube and slot, a shaft extending vertically from the lower casing, an upper casing rotatable on said 5 shaft and moved by a spring and having in its lower end recesses normally registering with said tubes and slots.

9. In a music-leaf turner, a lower fixed casting having therein oppositely-disposed vertical tubes and vertical slots in its opposite walls communicating with said tubes, leaf-turning arms slidably arranged at their inner ends in one of the tubes and slots, a spring-pressed follower for vertically moving said arms, a 15 shaft extending vertically from the lower casing, an upper casing rotatable by spring action on said shaft and having in its lower ends oppositely-disposed recesses normally registering with the tubes and slots, stops on the 20 upper casing, and a spring-pressed hand-controlled dog for locking and releasing said upper casing.

10. In a music-leaf turner, a lower fixed cas-

ing having in its opposite sides vertical recesses having oppositely-extending lateral extensions, leaf-turning arms slidably confined at their inner ends in said recesses, a spring-pressed follower for vertically moving said arms, said follower having a handle and adapted to be turned laterally to engage one of the 25 recess extensions to hold it in depressed position to permit the insertion of the arm ends in the opposite extension, a shaft extending vertically from the lower casing, an upper casing rotatable by spring action on said shaft 30 and having in its lower end recesses normally registering with the aforesaid recesses, stops for limiting the movements of the upper casing, and hand-controlled means for locking and releasing said upper casing. 40

In testimony whereof I affix my signature in presence of two witnesses.

HARRY L. WILSON.
